UNITED STATES PATENT OFFICE.

WILLIAM H. CURTIS, OF PORTLAND, OREGON, ASSIGNOR TO AUTO STROP SAFETY RAZOR COMPANY, OF NEW YORK, N. Y.

RAZOR.

Application filed June 14, 1922, Serial No. 588,292. Renewed February 11, 1926.

My invention relates to automatic stropping safety razors, such for example as the one sold in the market as the auto-strop.

The direct object of my invention is to provide mechanism in an automatic stropping safety razor which will prevent the cutting or nicking of the strop during the operation of stropping and also gives a greater degree of leverage to the device during the stropping operation.

Razors of the type mentioned are stropped without removing the blade from the holder, certain actuating rollers being so arranged as to cause reversal of the blade at the beginning of each stroke, these actuating rollers being caused to operate by the friction of the strop, which is held stationary. Wear on these actuating rollers or lost motion due to wear of the moving parts causes a slight slippage of the blade and holder at the beginning of the stropping stroke, before reversal of the blade takes place with the result that the blade often cuts into the strop. Frequently the strop is cut entirely in two and ruined for further use. My invention affords a positive and efficient remedy for this defect.

A further object of my invention is to provide a mechanism in which a firmer stropping stroke can be obtained than at present. In these types of razors as now constructed, the leverage obtainable between the strop and the blade is limited because they are very nearly parallel. In my invention it is possible to exert a greater degree of pressure of the blade on the strop because the blade holding head is pivotally mounted on the handle and therefore can be disposed angularly to the strop and can thus allow the cutting surface of the blade to be brought closer to the line of the applied force.

The details, mode of operation and particular features of my invention will be more readily understood by a description of the accompanying drawings, in which:

Fig. 1 is a front elevation of the complete razor;

Fig. 2 is a side elevation of Fig. 1;

Fig. 3 is a section taken approximately on the line 3-3 of Fig. 1, with the blade guard omitted showing the operating position of the razor, mechanism and strop at the end of a stropping stroke in the direction of the arrow;

Fig. 4 is a section similar to Fig. 3, ex-

cept that it shows the operating position of the razor, mechanism and strop at the beginning of a stropping stroke in the direction of the arrow; and

Fig. 5 is a fragmentary section and shows an adaption of the sleeve which will effectively eliminate play between the handle and the head.

For convenience I have illustrated my invention as applied to a self stropping safety razor of a well known type, but of course I do not limit myself to any particular type of self stropping safety razor.

The handle *a* holds the razor blade head during the operation of stropping or shaving and has a slot *s* milled in the upper part to receive and guide the movable part *b* which is pivotally connected to the handle by the pin *c*. The slot *s* is so cut as to leave a central portion projecting upward to form the stop *d*, the lower portion of part *b* being so formed as to engage stop *d* thereby limiting the pivotal movement of *b* to a predetermined amount.

A sleeve *f* is slidably mounted on the handle *a* and arranged to slip over lower portion of part *b* locking *b* rigidly in central position as shown in Figs. 1 and 2.

The sleeve *f* has internal screw threads *h* cut in the upper portion thereof so arranged to engage screw threads *h'* on the part *b* and to permit the sleeve *f* being locked in the position shown in Figs. 1 and 2.

A shoulder *f'* on the sleeve *f* is adapted to seat on the shoulder *a'* on the handle *a* and threaded to the head as at *h*, for eliminating any play between the head and the handle of the razor.

The frame *i* of the razor is rigidly af- fixed to part *b*. The guide rollers *j* and *j'*, actuating roller *j*² and blade carrying roller *j*³ are mounted in the frame, *i*.

The rollers *j*² and *j*³ are geared together by the gears *k* and *k'* (see Fig. 2) in such manner that *j*³ is actuated by *j*² in an opposite direction to the rotation of *j*². The blade *l* is suitably and detachably fastened to the roller *j*³. *m* represents a stop of suitable material.

A lever *o* has for its purpose, the raising and lowering of the blade guard *n*. Lowering of the blade guard *n* frees the blade *l* to enable the performing of the stropping operation. By holding the blade *l* against the blade guard *n* and then raising the blade guard *n* by means of the lever *o* the edges

of the blade are engaged in clips p and p' and thereby held in proper shaving position.

The operation of my invention may be described as follows:

The blade l is first disengaged from the blade guard n by lowering n by means of the lever o . The sleeve f , which is assumed to be in the position shown in Fig. 2 is then unscrewed disengaging threads h and h' and the sleeve f then slipped downward on handle a to any portion below the part b , such as shown in Figs. 3 and 4. The strop m is then inserted over rollers j and j' and under roller j^2 . If the razor now be pushed along the strop in the direction shown by the arrow Fig. 3, the frame i and blade l will assume the position shown, the blade being held firmly against the strop by the force of the friction of the strop on roller j^2 which is geared to the blade holding roller j^3 , as described. The position of the moving parts at the end of the stroke in the direction of the arrow will then be as shown in Fig. 3. At the beginning of the return stroke, since the razor is moved along the strop solely by means of the handle a , the moving parts will assume the position shown in Fig. 4, before the rollers j, j', j^2 and frame i start to slide on the strop inasmuch as these parts are pivotally connected to handle a by pin c . Stop d predetermines the amount of tilting action that takes place. This action of tilting the frame n before it actually starts moving along the strop raises the blade l from the strop to the position shown (Fig. 4) thereby positively preventing and avoiding any possibility of the blade cutting into the strop. Further movement of the razor in the direction of the arrow (Fig. 4) along the strop will cause the roller j^2 to function; since part b has engaged stop d , rotating the blade l in a clockwise direction, to the position shown by dotted lines r in which position blade l will be firmly held by the force of friction on roller j^2 as long as the razor is moved in the direction of the arrow in Fig. 4. Since the working parts are symmetrical it will readily be seen that the operation of the working parts will be relatively the same at the end of the second stroke and the beginning of the third stroke, as has just been described for the end of the first stroke and the beginning of the second stroke. Hence the operation may be repeated ad infinitum.

When the blade has been sufficiently stropped the strop is removed, the sleeve f is returned to the position shown in Fig. 2, and the blade engaged in clips p and p' on the blade guard n in the manner previously described and the razor is then ready to use.

I claim:

1. In a razor of the character described, a

head having a blade carrying roller and an actuating roller and means for imparting the rotation of the latter to the blade carrying roller, the head being adapted to have a strop inserted therethru on which said actuating roller bears, a handle on which said head is pivotally mounted so as to have limited angular movement with respect to the handle, whereby the movement of the handle in one direction causes a tilting of the head in the opposite direction lifting the blade from the strop in advance of the action of the actuating rollers, and means to limit pivotal movement of said head respecting said handle.

2. In a razor of the character described, a head having a blade carrying roller and an actuating roller and means for imparting the rotation of the latter to the blade carrying roller, the head being adapted to have a strop inserted therethru on which said actuating roller bears, a handle on which said head is pivotally mounted so as to have limited angular movement with respect to the handle, whereby the movement of the handle in one direction causes a tilting of the head in the opposite direction lifting the blade from the strop in advance of the action of the actuating rollers, and means to limit pivotal movement of said head respecting said handle.

3. In a razor of the character described, a head having a blade carrying roller and an actuating roller and means for imparting the rotation of the latter to the blade carrying roller, the head being adapted to have a strop inserted therethru on which said actuating roller bears, a handle on which said head is pivotally mounted so as to have limited angular movement with respect to the handle, whereby the movement of the handle in one direction causes a tilting of the head in the opposite direction lifting the blade from the strop in advance of the action of the actuating rollers, and means for securing the head firmly in vertical alinement with the handle.

4. In a razor of the character described, a head having a blade carrying roller and an actuating roller and means for imparting the rotation of the latter to the blade carrying roller, the head being adapted to have a strop inserted therethru on which said actuating roller bears, a handle having a socket in which said head is pivotally mounted, the adjacent portions of the handle and the head being spaced apart and provided with a groove and tongue respectively permitting limited angular movement of the head relative to the handle, whereby the movement of the handle in one direction causes a tilting of the head in the opposite direction lifting the blade from the strop in advance of the action of the actuating rollers, and a sleeve movable over the joint con-

necting the head and the handle to hold the head firmly in vertical alinement with the handle.

5. In a razor of the character described, a head having a blade carrying roller and an actuating roller and means for imparting the rotation of the latter to the blade carrying roller, the head being adapted to have a strop inserted therethru on which said ac-

10 tuating roller bears, a handle on which said head is pivotally mounted so as to have

limited angular movement with respect to the handle, whereby the movement of the handle in one direction causes a tilting of the head in the opposite direction lifting ¹⁵ the blade from the strop in advance of the action of the actuating rollers, and means cooperative between said head and handle to limit pivotal movement of said head in opposite directions.

WILLIAM H. CURTIS.
